UNITED STATES PATENT OFFICE

2,682,400

PREGATHERED FORM FEEDER

Robert K. Lukey, Chicago, Ill., assignor to W. F. Hall Printing Company, Chicago, Ill., a corporation of Illinois

Application June 21, 1952, Serial No. 294,947

9 Claims. (Cl. 270—54)

1

This invention relates to gathering machines adapted for use in the printing and binding industry to gather signatures located in different piles along the machine, the signatures being gathered in succession and in proper order to form books, magazines, etc.

In gathering signatures to form a book having a relatively large number of pages, it is customary to employ the use of several gathering machines, one of which pregathers a portion or form of the total signatures, which forms are stapled together and placed in a hopper of another gathering machine to be gathered with other signatures to complete the signature gathering operation. As a pre-gathered form may embody thirty or more signatures, it is difficult to successively withdraw the forms from the bottom of a hopper by conventional equipment designed to withdraw a single signature from the bottom of a hopper. The present invention contemplates the provision of a pre-gathered form feeder adapted to be incorporated into a conventional gathering machine to successively withdraw forms from the bottom of a hopper.

This invention further contemplates the provision of a pre-gathered form feeder which is relatively simple and inexpensive in construction, and adapted to be installed without difficulty upon a conventional gathering machine.

This invention further contemplates the provision of a pre-gathered form feeder embodying a feeder arm movable toward a hopper to engage and draw the stapled back of a form therein downwardly into position for engagement between a pair of gripper jaws provided on the end of a gripper arm. After the form has been engaged by the jaws, the feeder arm is moved to an inoperative position to permit the gripper arm to withdraw and transfer the form from the hopper to an endless conveyor employed to support the signatures and pre-gathered forms.

This invention embodies other novel features, details of construction and arrangement of parts which are hereinafter set forth in the specification and claims, and illustrated in the accompanying drawings, wherein:

Fig. 1 is a fragmentary front elevational view illustrating a signature gathering machine provided with a pre-gathered form feeder embodying features of the present invention.

Fig. 2 is a transverse sectional view taken along the line 2—2 of Fig. 1.

Fig. 3 is a fragmentary transverse sectional view taken along the line 3—3 of Fig. 1.

Fig. 4 is an enlarged sectional view taken along

2

the line 4—4 of Fig. 1, illustrating the pre-gathered form feeder arm disposed to engage a form in a hopper.

Fig. 5 is a sectional view corresponding to Fig. 4, illustrating the manner in which the feeder arm draws the stapled back of a form downwardly into position for engagement between the gripper jaws on a gripper arm.

Fig. 6 is a fragmentary front elevational view 10 showing the pre-gathered form feeder structure illustrated in Fig. 4.

Fig. 7 is a fragmentary top plan view of the pre-gathered form feeder.

Referring now to the drawings for a better 15 understanding of this invention, the pre-gathered form feeder is shown as applied to a conventional gathering machine comprising a drive shaft 2 journaled at spaced intervals along a frame 3 and acting through any suitable power 20 transmission means to drive an endless conveyor 4. The conveyor extends along the front of the machine and is provided at equally spaced intervals with push pins 6 to engage and advance the signatures to a binding machine (not shown). 25 As illustrated in Fig. 2, the inner flight of the conveyor travels along a trough 7 provided with a front wall 8 which serves as a stop for signatures 9 delivered to the trough.

The signatures 9 are arranged in stacks at 30 spaced intervals along the back of the machine to be gathered successively, each stack of signatures being disposed within a suitable hopper 11 embodying a bottom plate 12 and a front plate 13 having their adjacent edges spaced apart to define 35 an outlet 14 for the withdrawal of the bottom signatures from their respective stacks.

The signatures 9 are withdrawn from their respective stacks in timed relation with the travel 40 of the conveyor 4 to deposit the signatures at spaced intervals along the conveyor between the push pins 6. As illustrated in Fig. 3, a suction cup 16 is associated with each hopper 11 of a conventional gathering machine to withdraw the forward end of one signature at a time from the bottom of its related stack, the cups being mounted upon a sucker shaft 17 connected at its ends with members 18 hingedly connected at 19 with a stationary part of the machine. The suction cups are so disposed that when the structure just described is rocked on the hinges 19 in a counterclockwise direction (see Fig. 3) they pass upwardly through their respective hopper outlets 14 to engage the forward edge portions of the bottom signatures in the stacks and, when rocked 50 in the opposite direction, act to draw the forward

edge portions of their related signatures down through the outlets, in a manner well known in this art.

The shaft 17 and members 18 are actuated by a cam 21 keyed to the drive shaft 2 to engage a roller 22 on a lever 23 keyed to a shaft 24 which has a lever 26 keyed thereon to pivotally engage a link 27 connected to the members 18 at 28.

A conventional gripper feed mechanism is provided adjacent each hopper 11 to engage and deliver signatures 9 into the trough 7 for engagement by the push pins 6, each gripper mechanism comprising a gripper arm 35 keyed on a shaft 36 journaled on the frame of the machine, and each arm being provided with a fixed jaw 37 and a movable jaw 38 journaled on a pin 40. A rocker mechanism employed to swing the several arms 35 is shown as comprising a pair of levers 41 and 42 keyed to adjacent ends of shaft sections 36, the outer ends of the levers being connected by a pin 43. A pitman 44 is pivotally connected at its upper end to the pin 43 and is journaled at its lower end on a crank 45 formed on the drive shaft 9.

A connecting link 46 is pivotally connected at one of its ends to the movable jaw 38 and at its other end to one end of a rocker arm 48 pivotally mounted at 49 on a bracket 50 carried by the gripper arm 35. A connecting link 52 is pivotally connected at 51 to the rocker arm 48 and is pivotally connected at 53 to an arm 54 keyed to a shaft 55 journaled in fixed brackets 56-56. A sleeve 57 is secured to the shaft 55 and provided with an arm 58 pivotally connected at 59 to the upper end of a link 60, the lower end of the link being pivotally connected at 61 to the upper end of a link 62 and also to an arm 63 keyed to a shaft 65 journaled in brackets 66-66.

The lower end of the link 62 is pivotally connected at 67 to an arm 68 integral with a sleeve 69 journaled on the shaft 24. The sleeve 69 is formed with an arm 70 carrying a roller 71 engaging a cam 72 keyed to the shaft 2. The cams 21 and 72 are shaped and positioned to cause the movable jaw 38 to clamp a signature against the fixed jaw 37 when the gripping arm swings to its inner position adjacent the hopper 11, and to open the jaws to discharge the signature into the trough 7 when the arm is moved to its outer position.

While conventional gathering machines of the type thus described are suitable for use in gathering thin individual signatures, they are not designed or adapted for use in gathering relatively thick pre-gathered forms F comprising (for example) 25 or 30 signatures stapled together and arranged in stacked relation in a hopper 11.

To accommodate a conventional gathering machine for use in gathering pre-gathered forms F, a form feeder indicated generally at 75 is associated with the hopper 11 containing the forms F in place of the conventional suction cup 16. The form feeder is shown as comprising spaced brackets 76-76 secured to the sucker shaft 17 to support arms 77-77. Each arm 77 is pivotally mounted intermediate its ends at 78 upon its respective bracket and is normally biased against its stop plate 79 by means of a torsion spring 81. Each stop plate is adjustably mounted on its respective bracket by means of cap screws 82 passing through an elongated slot in the plate for threaded engagement in the bracket, to adjust the normal position of the arm 77 with respect to the bracket.

The upper end of each arm 77 is formed with a diagonal face 83 and provided with a pointed pin 84 projecting downwardly below said face to pierce the back of a form F in the hopper 11. Adjustably mounted on each arm 77 by means of a screw 86 is provided a seat member 87 to engage the bottom side of a form F, the seat member being adjustably positioned longitudinally of its arm toward and away from the pin 84 to coact with the latter in engaging the bottom form F in the stack.

A shaft 88 is journaled in bearings 89-89 secured on the frame 3 and has a pair of cam members 91-91 secured thereon. A shoulder screw 90 is threaded into each member 91 to serve as a journal for a roller 92 provided to engage the lower end of its respective arm 77 during rotational movement of the shaft 88. The shaft 88 is rotated in a counterclockwise direction, as shown in Fig. 4, by means of a chain drive leading from the drive shaft 2 through an endless chain 93 to a countershaft 94 and thence through an endless chain 96 to the shaft 88.

In the operation of the form feeder in withdrawing pre-gathered forms F from the bottom of a stack of forms in a hopper 11, the sucker shaft 17 and the brackets 76-76 secured thereon move back and forth along an arcuate path about the axis 19 in a common line of travel with adjacent suction cups 16 associated with adjacent hoppers 11.

When the shaft 17 and brackets 76-76 are swung about the axis 19 in a counterclockwise direction, as shown in Fig. 4, the cam faces 83-83 on the arms 77 engage the back of the lowermost form F in the stack and the seat members 87-87 engage the bottom side of said form. When the shaft 17 and brackets 76-76 are swung in a clockwise direction, from the position shown in Fig. 4 to the position shown in Fig. 5, the pointed pins 84-84 on related arms 77-77 penetrate the back of the lowermost pregathered form F to securely engage the arms to the form during subsequent downward movement of the arms relative to the hopper. When the shaft 17 reaches the end of its clockwise movement, shown in Fig. 5, the portion of the form F engaged by the arms 77-77 is bent downwardly into position to be engaged between jaws 37 and 38 on the gripper arm 35 associated with the hopper 11 containing the forms F.

During clamping engagement of a form F between the jaws 37 and 38, the arms 77-77 are pivoted clockwise, from their position illustrated in full lines to the position illustrated in dotted outline in Fig. 5, by the cam members 91-91 to dispose the arms out of the line of travel of the engaged form during transfer of the latter from the hopper to the trough 7 by the gripper arm 35. After withdrawal of a form F from the hopper, the rollers 92-92 move in a counterclockwise direction under and past their related arms 77-77 to permit the latter to be pivoted into engagement with their related stop plates 79-79 by their springs 81-81 to complete the operating cycle of the form feeder.

While this invention has been shown in but one form, it is obvious to those skilled in the art that it is not so limited but is susceptible of various changes and modifications without departing from the spirit and scope of the claimed invention.

I claim as my invention:

1. In a feed mechanism for drawing a pre-gathered form downwardly from the bottom of a hopper into position to be engaged between

gripper jaws on a gripper arm of a signature gathering machine, a sucker shaft movable upwardly toward and downwardly from the hopper, spaced brackets secured on the sucker shaft, a feeder arm pivotally connected intermediate its ends on each bracket, means including a pointed pin and a seat member on the upper end of each feeder arm to engage the back of a form in said hopper when the sucker shaft is moved upwardly and to draw the form downwardly from the hopper when said shaft is moved in the opposite direction to dispose the form in position for engagement by the gripper jaws, and actuating means to engage the lower ends of said feeder arms to pivot the upper ends of the arms away from a form after the form has been engaged by the gripper jaws.

2. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, spaced brackets secured on the sucker shaft, a feeder arm pivotally connected intermediate its ends on each bracket, means including a pointed pin and a seat member on the upper end of each feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower ends of said feeder arms to pivot the upper ends of the arms away from a form after the form has been engaged by the gripper jaws, stop plates adjustably positioned on said brackets, and springs normally urging the upper ends of said feeder arms toward said stop plates.

3. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, spaced brackets secured on the sucker shaft, a feeder arm pivotally connected intermediate its ends on each bracket, means including a pointed pin and a seat member on the upper end of each feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower ends of said feeder arms to pivot the upper ends of the arms away from a form after the form has been engaged by the gripper jaws, and means to adjust the position of said seat members relative to the pivot point of their respective feeder arms.

4. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, spaced brackets secured on the sucker shaft, a feeder arm pivotally connected intermediate its ends on each bracket, means including a pointed pin and a seat member on the upper end of each feeder arm to engage the back of a form in said hopper when the sucker shaft is moved upwardly and to

draw the form downwardly from the hopper when said shaft is moved in the opposite direction to dispose the form in position for engagement by the gripper jaws, actuating means to engage the lower ends of said feeder arms to pivot the upper ends of the arms away from a form after the form has been engaged by the gripper jaws, and a common drive means for said sucker shaft and said actuating means.

10 5. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, spaced brackets secured on the sucker shaft, a feeder arm pivotally connected intermediate its ends on each bracket, means including a pointed pin and a seat member on the upper end of each feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower ends of said feeder arms to pivot the upper ends of the arms away from a form after the form has been engaged by the gripper jaws, said actuating means comprising an actuating shaft rotatable beneath said arms, and cam members on said actuating shaft to engage and pivot said feeder arms.

35 6. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, feeder arm supporting means secured on the sucker shaft, a feeder arm pivotally connected intermediate its ends on said supporting means, means including a pointed pin and a seat member on the upper end of said feeder arm to engage the back of a form in said hopper when the sucker shaft is moved upwardly and to draw the form downwardly from the hopper when said shaft is moved in the opposite direction to dispose the form in position for engagement by the gripper jaws, and actuating means to engage the lower end of said feeder arm to pivot the upper end of the arm away from a form after the form has been engaged by the gripper jaws.

55 7. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, feeder arm supporting means secured on the sucker shaft, a feeder arm pivotally connected intermediate its ends on said supporting means, means including a pointed pin and a seat member on the upper end of said feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower end of said feeder arm to pivot the upper end of the arm away from a form after the form has been engaged by the gripper jaws, stop means provided on said feeder arm supporting means to be engaged by the upper end of the feeder arm, and means yieldably resisting movement of the upper

end of said feeder arm away from said stop means.

8. In a feed mechanism for drawing a pre-gathered form downwardly from the bottom of a hopper into position to be engaged between gripper jaws on a gripper arm of a signature gathering machine, a sucker shaft movable upwardly toward and downwardly from the hopper, feeder arm supporting means secured on the sucker shaft, a feeder arm pivotally connected intermediate its ends on said supporting means, means including a pointed pin and a seat member on the upper end of said feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower end of said feeder arm to pivot the upper end of the arm away from a form after the form has been engaged by the gripper jaws, stop means provided on said feeder arm supporting means to be engaged by the upper end of the feeder arm, means yieldably resisting movement of the upper end of said feeder arm away from said stop means, and a common drive means for said sucker shaft and said actuating means.

9. In a feed mechanism for drawing a pre-gathered form downwardly from the bottom of a hopper into position to be engaged between gripper jaws on a gripper arm of a signature gathering machine, a sucker shaft movable upwardly

toward and downwardly from the hopper, feeder arm supporting means secured on the sucker shaft, a feeder arm pivotally connected intermediate its ends on said supporting means, means including a pointed pin and a seat member on the upper end of said feeder arm to engage the back of a form in said hopper when the sucker shaft is moved upwardly and to draw the form downwardly from the hopper when said shaft is moved in the opposite direction to dispose the form in position for engagement by the gripper jaws, actuating means to engage the lower end of said feeder arm to pivot the upper end of the arm away from a form after the form has been engaged by the gripper jaws, stop means provided on said feeder arm supporting means to be engaged by the upper end of the feeder arm, means yieldably resisting movement of the upper end of said feeder arm away from said stop means, a common drive means for said sucker shaft and said actuating means, said actuating means comprising a rotatable actuating shaft, and cam means secured on said actuating shaft to engage and pivot the upper end of said feeder arm away from said stop means.
